UNITED STATES PATENT OFFICE

CHARLES GEORGE FOX, OF LONDON, ENGLAND

APPARATUS FOR DISTRIBUTING MATERIALS ON ROAD AND OTHER SURFACES

Application filed June 12, 1930, Serial No. 460,767, and in Great Britain July 9, 1929.

This invention relates to apparatus mounted upon road wheels and thus constituting a vehicle for use in distributing material, for instance, asphalt, bitumen, tar and pitch or the like, in a molten condition or in the form of aqueous emulsions on the surfaces of roads and is particularly concerned with apparatus for the purpose in question in which the material to be distributed is delivered to a rotary distributor including, for instance a chamber through which extends a shaft carrying a distributing member adapted to be rotated relatively to the walls of the chamber for the purpose of dispersing the material supplied thereto, the rotary distributor being actuated through the intermediary of an endless flexible member, such as a chain or belt or other driving connection from a wheel or wheels contacting with a road wheel.

The object of the invention is to provide an improved apparatus of the kind above referred to having means whereby the distance between the rotary distributor and the road or other surface to be treated, or in other words, the height thereof from the ground, may be varied.

In accordance with the invention, the rotary distributor is associated with means whereby it may be raised or lowered as a whole while maintaining constant the length of the driving connection between the same and a shaft on which a friction wheel or friction wheels contacting with a road wheel and actuating the distributor is or are mounted.

In one construction arcuate members, whose centres of curvature substantially coincide with the axis of rotation of the wheels contacting with the road wheels, are provided on the chassis or some portion of the frame of the vehicle and the distributor is arranged to be secured in position, through the intermediary of these arcuate members, at various points between their extremities, a flexible or pivotal tubular connection being provided between the container for the material to be distributed and the distributor.

For instance, in accordance with the invention, a pair of such arcuate members may be secured each by one of its ends to the tail of the vehicle or some other convenient

point on the frame or chassis, the other end of each of these arcuate members being secured to a stay extending at a suitable angle from the vehicle frame, means being provided on the distributor or member associated therewith whereby the same may be locked or secured to the arcuate members at any one of a plurality of positions, in order to vary the distance of the distributor from the road or other surface on to which material is to be deposited.

For adjustably securing the distributor to the arcuate members a plurality of holes may be provided in the latter through which and corresponding holes in a member associated with the distributor bolts or the like may be passed in order to maintain the distributor in the desired position with respect to the surface to which the material is to be deposited thereby.

In an alternative construction the distributor is rigidly secured to arcuate members adjustably mounted upon the vehicle.

If desirable or necessary, the tubular connection between the distributor and the container for the material to be distributed may be arranged to be extended or contracted according to the position in which the distributor is adjusted. As above indicated, the connection may be constituted by a flexible pipe or the like. Alternatively, the pipe may be provided with elbows mounted in glands or the like provided on the distributor and on the container for the material to be distributed or an extension thereof and in this case the pipe may be telescopic, or comprise a telescopic portion.

The invention will be described further in detail with reference to the accompanying drawings, in which:—

Figure 1 illustrates the tail portion of the frame of a vehicle furnished with a rotary distributor, while

Figures 2 and 3 are, respectively, views in plain and elevation illustrating one convenient construction of distributor, and

Figures 4 and 5 are corresponding views of an alternative construction of distributor.

Referring to Figure 1, 1 represents the tail portion of the frame of the vehicle, 2

- one of a pair of arcuate members secured thereto and to a stay 3 also connected with the frame of the vehicle, 4 is the casing enclosing the driving gear for the rotary distributor which is located within the conical housing 5, 6 is a sprocket through which the driving mechanism of the distributor is operated, the sprocket in question being in driving connection by means of the chain 7 with 5 the sprocket 8 mounted upon the same shaft as the wheel 9 which makes frictional contact with one of the road wheels 10 of the vehicle. 11 is an outlet for the emulsion from a tank 11a which is located on the frame of the vehicle, 12 is an elbow pivotally connected therewith and provided with an extension 13 telescopically engaging the elbow 14 which is pivotally mounted in the conical housing of the distributor.
- 10 The distributor is shown in full line in its extreme upper position and in dotted line in its extreme lower position and, as shown in the drawings, it is connected with the cross member 15 and the distributor may be secured in the positions indicated in the drawings or in any of a plurality of intermediate positions by means of bolts passed through flanges on the end of the member 15 and holes 16 in the arcuate members.
- 15 As will be understood, the distributor could, conveniently, be secured in association with arcuate members generally equivalent to the arcuate members 2 which in turn are secured to the outer ends of stays 3, the other ends of which instead of being secured rigidly to the tail portion of the frame of the vehicle, as in the above construction, are provided with bearings engaging pins on the frame and in this case for securing the distributor at the desired height from the ground, holes equivalent to the holes 16 would, conveniently, be provided in the arcuate members, such holes being arranged to be engaged by a pin or pins passing through 20 one or other of the holes and engaging in corresponding holes in means associated, for instance, with the cross member, the distributor being, with this construction, rigidly secured to the arcuate members instead 25 of being movable relatively thereto as in the construction previously described.

Suitable forms of rotary distributors for use in apparatus in accordance with the invention are, as above indicated, illustrated 30 in Figures 2, 3, 4 and 5 in which 17 is the housing for the distributor, connected as above described with the arcuate members 2, 18 is the inlet for the material to be distributed and 19 a shaft forming a driving connection between the sprocket 6 (see Figure 1) and the distributor.

In the construction illustrated in Figures 2 and 3, the housing terminates in a portion 20 of conical form, the lower edge 21 of which is 35 upturned to provide a peripheral channel 22

into which a liquid fuel may be introduced and ignited for the purpose of heating the device, a conical member 23 provided with holes 24 being secured to the lower end of the housing. Adjacent to the outer face of the said member and secured to the aforesaid shaft is a member 25 provided with a plurality of arms, the sides of which are notched as shown in Figure 2.

70 In the construction illustrated in Figures 4 and 5, the shaft 19 is secured to a conical bowl 26 provided with co-axial partitions 27 forming annular spaces 28, and the bottom of the bowl is provided with openings 29 as shown in Figure 4.

75 In both of the constructions illustrated, the housing is provided with an inwardly directed flange 30 for the purpose of directing material entering through the inlet 18 towards the centre of the distributor.

80 The material to be distributed on the road surface is supplied by way of the inlet 18 from the container to the space within the conical portion of the housing, and passing out by way of the holes 24 or 29, is, by rotation of the member provided with arms 25 (see Figures 2 and 3) or of the conical bowl 26 (see Figures 4 and 5) projected or distributed over the road surface.

85 It is to be pointed out that the above detailed description is furnished for the purpose of assisting in the understanding of the nature of the invention and particularly describing certain constructions falling within its scope and that various changes may be 90 made in the details of construction and arrangement without exceeding the scope of the invention.

95 Having now described my invention what I claim as new and desire to secure by Letters Patent is:—

100 1. Apparatus for use in distributing material in a fluid condition on the surfaces of roads comprising a vehicle mounted upon road wheels, a rotary distributor associated therewith, means adapted to frictionally engage one of said road wheels in order to actuate the rotary distributor, a driving connection between the first-mentioned means and the rotary distributor, and arcuate members secured to the vehicle and engaging the rotary distributor to permit raising or lowering of the same as a whole to vary its distance from the road surface while maintaining constant the length of the driving connection between the first-mentioned means and the rotary distributor.

110 2. Apparatus for use in distributing material in a fluid condition on the surfaces of roads comprising a vehicle mounted upon road wheels, a container for material to be distributed associated therewith, a rotary distributor associated with said vehicle, flexible means connecting the container with the rotary distributor, a friction wheel mounted 115

- on a shaft and adapted frictionally to engage one of said road wheels in order to actuate the rotary distributor, a driving connection between the friction wheel and the 5 rotary distributor, and arcuate members adapted to engage the rotary distributor and to secure the same at any one of a plurality of distances above the road surface while maintaining constant the length of the 10 driving connection between the shaft and the rotary distributor.
3. Apparatus for use in distributing material in a fluid condition on the surfaces of roads comprising a vehicle mounted upon 15 road wheels, a rotary distributor associated therewith, a friction wheel mounted on a shaft and adapted frictionally to engage one of said road wheels in order to actuate the rotary distributor, a driving connection between the said friction wheel and the rotary distributor, arcuate members located on said vehicle and adapted at various points between their extremities to engage the rotary distributor and to secure the same at any 20 25
- one of a plurality of distances from the road surface while maintaining constant the length of the driving connection between the shaft and the rotary distributor.
4. Apparatus for use in distributing material in a fluid condition on the surfaces of roads comprising a vehicle mounted upon road wheels, a rotary distributor associated therewith, a friction wheel mounted on a shaft and adapted frictionally to engage one 30 35
- of said road wheels in order to actuate the rotary distributor, a driving connection between the said friction wheel and the rotary distributor, arcuate members located on said vehicle, means adapted to secure the rotary 40 45
- distributor to the arcuate members at any one of a plurality of positions in order to vary the distance of the rotary distributor as a whole from the road surface while maintaining constant the length of the driving connection between the shaft and the rotary distributor.
5. Apparatus for use in distributing material in a fluid condition on the surfaces of roads comprising a vehicle mounted upon 50 road wheels, a container for material to be distributed associated therewith, a rotary distributor associated with said vehicle, flexible means connecting the container with the rotary distributor, a friction wheel mounted 55 60
- on a shaft and adapted frictionally to engage one of said road wheels in order to actuate the rotary distributor, a driving connection between said friction wheel and the rotary distributor, arcuate members located on said vehicle, means adapted to secure the rotary distributor to the arcuate members at any one of a plurality of positions in order to vary the distance of the rotary distributor as a whole from the road surface while maintaining constant the length of the driving 65 70 75
- connection between the shaft and the rotary distributor.
6. Apparatus for use in distributing material in a fluid condition on the surfaces of roads comprising a vehicle mounted upon road wheels, a rotary distributor associated therewith, a friction wheel mounted on a shaft and adapted frictionally to engage one of said road wheels in order to actuate the rotary distributor, a driving connection between the said friction wheel and the rotary distributor, arcuate members provided with holes located on said vehicle, a member associated with the rotary distributor and provided with holes corresponding with the holes in the arcuate members, bolts adapted to engage within the said holes to secure the rotary distributor to the arcuate members at any one of a plurality of positions in order to vary the distance of the rotary distributor as a whole from the road surface while maintaining constant the length of the driving connection between the shaft and the rotary distributor.
7. Apparatus for use in distributing material in a fluid condition on the surfaces of roads comprising a vehicle mounted upon road wheels, a container for material to be distributed associated therewith, a rotary distributor associated with said vehicle, flexible means connecting the container with the rotary distributor, a friction wheel mounted on a shaft and adapted frictionally to engage one of said road wheels in order to actuate the rotary distributor, a driving connection between the said friction wheel and the rotary distributor, arcuate members provided with holes located on said vehicle, a member associated with the rotary distributor and provided with holes corresponding with the holes in the arcuate members, bolts adapted to engage within the said holes to secure the rotary distributor to the arcuate members at any one of a plurality of positions in order to vary the distance of the rotary distributor as a whole from the road surface while maintaining constant the length of the driving connection between the shaft and the rotary distributor.
8. Apparatus for use for distributing material in fluid condition on the surfaces of roads comprising a vehicle mounted upon road wheels, a container for material to be distributed associated therewith, a conical housing associated with said vehicle, flexible means connecting the container with the said housing, a shaft rotatably mounted in said housing, a conical bowl provided with coaxial partitions, secured to said shaft and adapted upon rotation of the same to distribute the material over the road surface, a friction wheel adapted to engage one of said road wheels in order to actuate the said conical bowl, a driving connection between said friction wheel and the shaft, arcuate members 115 120 125 130

located on said vehicle and provided with holes, a member associated with the conical housing and provided with holes corresponding with the holes in the arcuate members' 5 adapted to accommodate bolts to secure the conical housing to the arcuate members at any one of a plurality of positions above the road surface while maintaining constant the length of the driving connection between the 10 second mentioned shaft and the shaft secured to the conical bowl.

9. Apparatus for use in distributing material in a fluid condition on the surfaces of roads, comprising a vehicle mounted upon 15 road wheels, a tank for material to be distributed associated therewith, a rotary distributor associated with the vehicle, means adapted to frictionally engage one of said road wheels in order to actuate the rotary 20 distributor, a driving connection between the first-mentioned means and the rotary distributor, an adjustable support for the rotary distributor connected with the vehicle adapted to permit raising or lowering of the same as a 25 whole to vary its distance from the road surface while maintaining constant the length of the driving connection between the first-mentioned means and the rotary distributor, and a swivelling tubular connection between 30 the rotary distributor and the tank.

10. Apparatus for use in distributing material in a fluid condition on the surfaces of roads, comprising a vehicle mounted upon road wheels, a tank for material to be distributed associated therewith, a rotary distributor associated with said vehicle, flexible means 35 connecting the container with the rotary distributor, a friction wheel mounted on a shaft and adapted frictionally to engage one of 40 said road wheels in order to actuate the rotary distributor, a support for the rotary distributor connecting the same with the vehicle, and fastening means associated with the support adapted to secure the rotary distributor 45 at any one of a plurality of distances above the road surface while maintaining constant the length of the driving connection between the shaft and the rotary distributor.

In testimony whereof I have signed my 50 name to this specification.

CHARLES GEORGE FOX.
